UNITED STATES PATENT OFFICE

CLARA C. FRYE, OF TAMPA, FLORIDA.

SURGICAL APPLIANCE.

No. 847,758.

Specification of Letters Patent.

Patented March 19, 1907.

Application filed May 9, 1906. Serial No. 316,024.

To all whom it may concern:

Be it known that I, CLARA C. FRYE, a citizen of the United States of America, residing at Tampa, in the county of Hillsboro and 5 State of Florida, have invented certain new and useful Improvements in Surgical Appliances, of which the following is a specification.

This invention relates to new and useful improvements in surgical appliances; and it is the intention of the invention to provide a device which may be termed a "combination" chair and bed.

It is an object of the invention to provide 5 a novel device of this kind that may be employed for obstetrical purposes, in cases of fever, or in any case of sickness.

It is also an object of the invention to provide a novel device of this character employing a cushion that may be inflated with air or filled with hot or iced water according as the necessities of practice may require.

The invention also has for an object the provision of a novel device of this character wherein a bed-pan may be employed with little trouble to or disturbance of the patient.

A further object of the invention is to provide a novel device of this kind that will be simple in construction, efficient in practice, and economical to manufacture.

With the above and other objects in view the invention consists in the details of construction and in the arrangement and combination of parts to be hereinafter more fully described.

In describing the invention in detail reference will be had to the accompanying drawings, forming part of this specification, wherein like characters of reference denote corresponding parts in the several views, and in which—

Figure 1 is a top plan view of the device, the same being in a flat position. Fig. 2 is a view in side elevation of the main frame. Fig. 3 is a view in side elevation of secondary or sectional frame. Fig. 4 is a top plan view of the cushion employed in this invention. Fig. 5 is a view in elevation of a limb-brace employed in the invention, said brace being detached. Figs. 6 and 7 are views of the handholds employed with the invention. Fig. 8 is a view in elevation of the invention, showing the parts of the sectional frame in various adjustments. Fig. 9 is a view in elevation of a stand employed with the device. Figs. 10 and 11 are detail views.

In the drawings, 2 indicates the main frame of the chair, which is made of tubing or other suitable material and is preferably rectangular in contour. Extending across 60 the frame at intervals intermediate its length are the supporting-rods 3, which may be secured to the main frame 2 in any desired manner, but preferably by the T-joints 4. Centrally of the frame 2 at opposite sides are 65 the upwardly-extending ears 5, provided with the openings 6, in which are mounted the ends of the cross-rods 7.

The chair comprises in its construction a series of pivoted sections 8 9 10 and a pivoted 70 head-section 11, it being understood that each section is pivoted to the next succeeding section. The section 9 may be termed the "base" or "main" section, the section 8 the "foot-section," and section 10 the "back-section." The sections 9 and 10 are not only pivoted one with relation to the other, but are pivotally held by the cross-rod 7. By this arrangement the chair-sections are held 75 to the main frame 2. On the sides of the 80 back section 10 of the chair are arranged the racks 11', which are engaged by the yokes 13 and 14. These yokes are for adjusting the incline of the back. Both of the yokes are pivotally secured to the frame, yoke 13 being 85 larger or longer than yoke 14 for the purpose which is thought to be plainly apparent. Arranged between the lower end of the frame 2 and the adjacent cross-strip or supporting-rod 3 are the rack-strips 15, which are engaged by the end of the foot-section 8 for the 90 purpose of elevating the base-section for the insertion therebeneath of the bed-pan 16. This bed-pan is made of white enamel-ware and is open at the top, so that it may be 95 easily cleaned. It is provided with the hinged cover 17, having the usual opening 18. The base-section 9 is also provided with an opening 19, which is formed by holding within the base-section the frame 20 of tubing or 100 the like by means of the rods 21, which are secured to the frame 20, and the base section 9 by the T-couplings 22. The head-section is adjustable with relation to the back-section by means of the rod 23, pivoted at one 105 end to the head-section and having near its opposite end an elongated slot 24, through which passes the binding-screw 25, carried by the back-section. Each of the chair-sections is provided with a backing of woven 110 wire which will prove sanitary and not too rigid.

Employed with the chair is an inflatable cushion 26, which is of the same form or shape as the chair. The cushion is provided along its edges with ears or extensions 27, 5 having the apertures 28. By means of these apertures the cushion is secured to the chair by cords or other securing means, as will, it is thought, be readily appreciated. That portion of the cushion arranged over the base 10 section 9 of the chair is provided with an opening 29 to register with the opening 19 of the bed-pan when in position. A cover 30 is employed for said opening, this cover being also inflatable.

15 The cushion is formed, preferably, of rubber and is provided at one corner with a valve for admitting air when the device is to be used as an air-bed, and at the adjacent corner it is provided with a larger valve for 20 admitting water or other fluid. When being used for fever, it may be necessary that iced water be employed, while for other diseases hot water may be necessary. It is the intention of the invention to provide a cushion 25 for either air, hot, or cold water.

When the chair is to be used for obstetrical purposes, a stand or support is employed which comprises in its construction the corner-posts 31, which are tubular to receive the 30 extensions 32. By means of the extensions the height of the stand can be regulated. The extensions are held in their varying adjustments by means of the screws 32, which are threaded through the posts 31 and bind 35 against the extensions 32. The chair or frame rests upon the extensions 31 and is clamped thereto in any ordinary or preferred manner. When employed for obstetrical

purposes, the limb-braces 33 are used. These braces each comprise a tubular section *a*, 40 which has an end bifurcated to embrace a side of the frame, the same being clamped thereon by means of the screw *b*. Adjustably held in the tubular section is an angular section *c*, from which depends a padded 45 leather bracelet *d*. Handholds 34 are also used. These holds each comprise a rod having one end formed to embrace the frame, the opposite end being provided with a hand grasp. These holds are held to the frame by 50 means of the set-screws 35. The back of the cushion 26 is provided with a heavy canvas covering to protect the same against wear.

Having thus fully described my invention, what I claim as new, and desire to secure by Letters Patent, is—

In combination, a main frame, cross-strips carried by the main frame, ears on opposite sides of the main frame, a cross-strip secured in said ears and a secondary frame within the 60 main frame, said secondary frame comprising sections pivotally secured one to the other and to the cross-piece of the main frame carried by the ears, one of the sections adjacent said cross-strip being provided with 65 an opening, said main frame having a plurality of cross-strips positioned beneath the opening in said section, said cross-strips being intended to support a receptacle.

In testimony whereof I affix my signature, 70 in the presence of two witnesses, this 25th day of April, 1906.

CLARA C. FRYE.
